CLAIM

We claim the ornamental design for a detailing polisher, substantially as shown and described.

DESCRIPTION

FIG. 1 is a perspective view of the detailing polisher according to our new design;

FIG. 2 is a right side elevational view of the detailing polisher of FIG. 1;

FIG. 3 is a top plan view of the detailing polisher of FIG. 1;

FIG. 4 is a bottom plan view of the detailing polisher of FIG. 1;

FIG. 5 is a left side elevational view of the detailing polisher of FIG. 1;

FIG. 6 is a front elevational view of the detailing polisher of FIG. 1; and,

FIG. 7 is a rear elevational view of the detailing polisher of FIG. 1.

The broken line showing of a broken away electrical cord is for illustrative purposes only and forms no part of the claimed design.
